CIGARETTE LIGHTER OR SIMILAR ARTICLE

Olle E. Haggstrom, Trumbull, Carl N. Johnson, Stratford, and William V. Judson, Westport, Conn., assignors to General Electric Company, a corporation of New York

Filed June 14, 1965, Ser. No. 85,710

Term of patent 3½ years

(Cl. D48—27)

Fig. 1.

Fig. 2.

Fig. 5.

Fig. 3.

Fig. 6.

Fig. 4.

FIG. 1 is a front perspective view of a cigarette lighter embodying our new design;

FIG. 2 is a front elevational view of the cigarette lighter shown in FIG. 1;

FIG. 3 is a left side elevational view of the cigarette lighter shown in FIG. 1;

FIG. 4 is a right side elevational view of the cigarette lighter shown in FIG. 1;

FIG. 5 is a bottom plan view of the cigarette lighter shown in FIG. 1; and

FIG. 6 is a top plan view of the cigarette lighter shown in FIG. 1.

The side opposite that shown in FIGS. 1 and 2 is a substantial mirror image of the side shown.

We claim:

The ornamental design for a cigarette lighter or similar article, substantially as shown and described.
